JAMES B. MACDUFF, OF NEW YORK, N. Y.

Letters Patent No. 75,558, dated March 17, 1868.

MODE OF FORMING RAISED ORNAMENTS ON WOOD.

The Schedule referred to in these Letters Patent and making part of the same.

TO ALL WHOM IT MAY CONCERN:

Be it known that I, JAMES B. MACDUFF, of New York, in the county of New York, and State of New York, have invented a new and useful Improvement in the Mode of Forming Raised Ornaments upon Wood; and I do hereby declare that the following is a full, clear, and exact description thereof, which will enable others skilled in the art to make and use the same, reference being had to the accompanying drawings, forming part of this specification, in which—

Figure 1 is a perspective view of the knife used in giving form to the ornament.

Figure 2 is a vertical section of the same, taken through the line x x , fig. 1.

Figure 3 is a perspective view of the follower, by which the ornament is pressed down into the wood.

Figure 4 is a perspective view of a block of wood in which the ornament has been pressed down, and the surrounding wood partly cut away.

Figure 5 is a perspective view of a block of wood, showing the surrounding wood cut away; and the ornament swelled out or raised.

My invention has for its object to furnish an improved, simple, and convenient mode by means of which letters, scrolls, or other raised ornaments, may be formed upon wood; and it consists in the mode of accomplishing this, as hereinafter more fully described.

A is a knife, which is made of the exact shape and size of the letter or ornament to be formed upon the wood. The knife A is then forced into the wood a little deeper than it is desired that the ornament should project when finished. The knife A is then removed, and the follower B, the face of which is made of the exact form of the desired ornament, is forced down, compressing the ornament into the block as far or a little farther than it is desired that the ornament should project when finished, leaving the wood around the said compressed ornament projecting, as shown in fig. 4. The wood projecting around the letter or ornament is then sawn off, or otherwise removed, as shown at the point C, fig. 4.

By sawing off the wood surrounding the ornament, the part sawn off may be used for forming sunken or depressed ornaments. The block or board is then steamed or exposed to the action of alcohol, water, or other similar agent, by which the compressed wood is expanded or raised to its former state, and the letter or other ornament stands projecting above the other parts of the block or board.

By repeating the operation two or more times, complex ornaments, or ornaments, parts of which project higher than other parts, may be formed.

I claim as new, and desire to secure by Letters Patent—

Raising ornaments upon wood by means of the knife A and follower B, operated as described, whereby the knife is forced into the wood and removed, and the follower B applied to compress the ornaments, which, after the blank is sawed off, are raised to the desired height by steaming, as herein shown and described.

The above specification of my invention signed by me, this 18th day of June, 1867.

JAMES B. MACDUFF.
